ALUMINUM TO COPPER CONNECTOR

Wallace L. Cook and William J. Buehring, Chicago, Ill., assignors to Reliable Electric Company, Chicago, Ill., a corporation of Illinois

Application April 16, 1938, Serial No. 202,379

3 Claims. (Cl. 174—94)

- The present invention relates to connectors for connecting aluminum wires and steel wires to copper wires. When aluminum and steel wires are connected to copper wires, there is always the danger of galvanic corrosion whenever moisture lodges between the wires. If a drop of moisture lodges between the wires, the corrosion immediately begins and the aluminum wire is quickly corroded away.
- 10 The present invention contemplates the provision of a connector wherein this difficulty is avoided to a substantial degree. It is particularly directed toward the provision of a separator member which comprises a thick block of 15 aluminum. The separator member separates the unlike wires sufficiently to prevent a drop of moisture from lodging between them and thus effecting a bridge which will cause galvanic corrosion of the aluminum wire.
- 20 The features and advantages of the invention will appear more fully as the description proceeds, reference being had to the accompanying drawing, wherein a preferred form of the invention is shown. It is to be understood, however, that the drawing and description are 25 illustrative only, and are not to be taken as limiting the invention except insofar as it is limited by the claims.
- In the drawing, Fig. 1 is a sectional view through a connector embodying the invention; Fig. 2 is a perspective view of the separating member employed in Fig. 1;
- Fig. 3 is a sectional view through another form of connector to which the invention is applicable;
- Fig. 4 is an enlarged plan view of a separator member used in the connector shown in Fig. 3;
- Fig. 5 is a sectional view taken on the line 5—5 of Fig. 4; and
- 40 Fig. 6 is a perspective view of a clamping element used in the connector shown in Fig. 3.
- Referring now to the drawing, the connector shown in Fig. 1 comprises a clamping body 5 which is substantially U-shaped to provide a slot 45 between the legs 6 and 7 thereof to receive wires 8 and 9. The wires 8 and 9 are laid in the slot in substantially parallel relation and are spaced from each other by a separator member 10. The separator member 10 preferably is a rectangular 50 aluminum block of substantial thickness, as shown in Fig. 2. It is provided with conductor receiving grooves 11 and 12 in the opposite faces thereof. The clamping body 5 has flanges, shown at 13 and 14, for guiding the member 10 between the legs 6 and 7.
- The wire 8 is held in the groove 11 of the clamping element 15. The element 15 is adapted to slide transversely of the slot between the legs 6 and 7 through suitable openings 16 and 17. The element 15 has notches 18 and 19 which engage the legs 6 and 7 and prevent their spreading when pressure is applied in clamping the wires together. Although not important to the present invention, the end construction of the element 15 is such that it cannot be removed 10 from the leg 7. The construction thereof may desirably be that shown in the patent to Fotsch No. 2,107,859.
- The member 10 is of sufficient thickness that it separates the copper wire 9 from the aluminum wire 8 sufficiently to prevent a drop of moisture from lodging between the wires at either side of the connector. The member 10 has a bi-metallic sheet 20 fastened thereto over the conductor receiving groove 12. The bi-metallic sheet 20 consists of a layer 21 of aluminum and a layer 22 of copper. The sheet 20 has its side edges 23 and 24 bent up to form flanges that are secured in grooves in the member 10. The sheet 20 is thus staked firmly in place on the member 10, and the fastening means by which it is staked, that is the flanges 23 and 24, are outside the line of contact between the wires and the separator member. Some corrosion will take place where the sheet is staked into the member 10 because there direct contact is made between the copper part of the sheet 20 and the member 10. This, however, is not detrimental to such a degree as direct corrosion of the wire 8 would be because it is not in the conducting path. The bi-metallic sheet 20 is so constructed that the copper and aluminum parts thereof are integrally joined and no moisture can get between them.
- The wires are clamped in place by a clamping means consisting of a second element 25 which also is desirably an aluminum block and which has a bi-metallic sheet 26 similar in all respects to the sheet 20 staked thereto for engagement with the wire 9. The element 25 is 45 engaged by a screw bolt 27 that is threaded into one end of the body 5. The flanges 13 and 14 serve to hold the element 25 in place.
- Referring now to Fig. 3, the invention is shown here as applied to a connector of the 50 split bolt type wherein the clamping body consists of a split bolt 30 having leg portions 31 and 32 screw threaded to receive a nut 33. The split bolt 30 is preferably made of aluminum so that an aluminum wire 34 may be clamped thereto.

without setting up any corrosion. In order to connect a copper wire 35 to the aluminum wire 34 by means of this connector, we provide a separator member 36 which is shown in enlarged form in Fig. 4. This separator member has conductor receiving grooves 37 and 38 in the opposite sides thereof and the groove 38 is covered by a bi-metallic sheet 39 similar in all respects to the sheet 20 in construction, that is, it has the aluminum part thereof directly in engagement with the member 36 and has a copper layer for engagement with the wire 35. In this form of the invention, however, the staking flanges 40 and 41 do not extend full length of the sheet 39, but are provided only at the ends thereof. There are four staking flanges 40 and 41 which are embedded in suitable grooves provided in the member 36. To facilitate guiding the member 36 between the legs 31 and 32, this member is provided with cut-out guides 42 and 43.

The wire 35 is adapted to be clamped between the sheet 39 and a similar sheet 44 which is carried upon a clamping element 45. The clamping element 45 is mounted in the nut 33 and has ears 46 and 47 which are bent over after the element 45 is inserted in the nut so as to rotatably mount this element. The sheet 44 is staked in the element 45 by flanges 48 and 49. It is possible, of course, to obtain adequate separation by using just a plain aluminum slug of sufficient thickness between the copper wire and the aluminum wire. However, this makes a corrosive mass next to the copper wire with a resultant high resistance across the shortest conducting path between the wires. A copper shim between the copper wire and the aluminum slug member would also tend to make a similar corrosive mass in the conducting path, even though it were spaced from the copper tap wire. In the present device, the only spot for corrosive action to take place is outside the pressure line and the main conducting path. It is only at the line where the bi-metallic strip is staked into the aluminum member 10 and here the copper is between the aluminum of the member 10 and the aluminum of the bi-metallic element. Since these two pieces of the same metal are neutral to each, the accelerated corrosion and consequent increase in resistance in the conducting path are avoided.

The split bolt connector shown in Figs. 3-6 inclusive is made up of three pieces, insofar as the lineman is concerned, because the nut 33 and the element 45 are joined together. The member 36 is, of course, a separate member. However, the member 45 may be connected to one of the legs of the split bolt 30 in any one of the well-known ways now common in this art.

In the connector shown in Fig. 1, the element 15 cannot be lost from the body 5, and therefore from the lineman's standpoint this is only a one-piece connector. The body 5 which is desirably of hot galvanized steel carries all of the parts.

The member 10 normally is not removable past the element 15. It can, however, be removed by spreading the parts 13 and 14 slightly to permit the member 10 to pass the end of the element 15. This is only necessary when it is desired to insert a continuous copper wire 9 in the slot between the member 10 and the element 25.

Having thus described our invention, what we claim as new and desire to secure by Letters Patent is:

1. Means for connecting aluminum or steel wires to copper wires, comprising a clamping body having an open ended slot in which the unlike wires are laid in parallel relation, an aluminum member separating the wires sufficiently to prevent a drop of moisture from bridging the space between the wires, said member having a bi-metallic aluminum copper sheet fastened to the side thereof next to the copper wire, with the copper side of said sheet toward the copper wire, an aluminum clamping element in said slot for pressing the copper wire toward said member, said element having a bi-metallic aluminum copper sheet fastened to the side thereof toward the copper wire, with the copper side of said sheet toward the copper wire, an aluminum element for pressing an aluminum or steel wire against the side of said separator member opposite the copper wire and means adjustably mounted on said body for forcing said elements toward each other.

2. In a connector for electrically connecting aluminum or steel wires to copper wires, an aluminum separator member which separates the unlike wires sufficiently to prevent a drop of moisture from lodging between the wires and causing galvanic corrosion, and a bi-metallic sheet fastened to the aluminum member on the side thereof next to the copper wire, said sheet comprising copper on the wire engaging side and aluminum on the member engaging side, said sheet having flanges at the side edges thereof spaced from the wire engaging part thereof and embedded in the separating member to hold the sheet in place.

3. In a connector for electrically connecting aluminum or steel wires to copper wires, separating means which separate the unlike wires sufficiently to prevent a drop of moisture from lodging between the wires and causing galvanic corrosion, said separating means being composed of aluminum with a copper sheet facing integrally fixed to a part of the aluminum on the copper wire side of said means, the exposed junction of the copper sheet and aluminum being spaced from the area of contact between the copper wire and the separating means, whereby any corrosion at said junction is outside the conduction path between the wires, said copper sheet having flanges at the side edges thereof and said aluminum separating means having grooves in which the flanges of the copper sheet are embedded.

WALLACE L. COOK.
WILLIAM J. BUEHRING.
